UNITED STATES PATENT OFFICE.

PATRICK REILLY, OF MATTOON, ILLINOIS.

CAR-TRUCK.

SPECIFICATION forming part of Letters Patent No. 279,185, dated June 12, 1883.

Application filed March 16, 1883. (No model.)

To all whom it may concern:

Be it known that I, PATRICK REILLY, a citizen of the United States, residing at Mattoon, in the county of Coles and State of Illinois, have invented a new and Improved Freight-Car Truck, of which the following is a specification.

My invention relates to the combination of novel strengthening and sustaining plates, preferably of cast metal, with the wrought-metal arch-bars of the side frames of freight or heavy burden car trucks, whereby the weakness of and difficulty experienced from such trucks giving out by the arch-bars springing out of place is avoided and overcome.

The object of my invention is to strengthen the truck at the points where practical tests have demonstrated it is most liable to break. The tests made with respect to this class of car-trucks have proved that they all give out by the arch-bars springing out of place; and to prevent such springing of these bars, when under great strain and pressure, I have contrived the invention of providing properly-shaped and strong yet light metal plates, preferably of cast metal and skeleton in form, and bolting these plates between the arch-bars, as will be more fully understood from the accompanying drawings, in which—

Figure 1 represents a view of my improved truck partly in elevation and partly in vertical section, and Fig. 2 a vertical cross-section of one of the side frames in the line $x-x$ of Fig. 1.

The side of truck-frame A, as represented, is of ordinary construction, being the style almost universally used. Within the spaces formed by the converging and united arch-bars $a-a$ of the side frame I apply metal plates B of a form corresponding in outline to the spaces in which they are fitted, as shown. These plates in cross-section in any direction are of angle-iron form, in order that they shall have the necessary strength and yet not be too heavy, as shown at b, Fig. 2. The width of the bearing afforded by the plates is equal to the width of the arch-bars $a-a$. In the drawings I have represented the plates as triangular in form and as abutting into the corner formed at the meeting points of the arch-bars

$a-a$. The plates B are also shown as terminating at their vertical edges on one side of the vertical supporting columns and bolts, as at C C of the truck-frame, and they are shown as made of cast metal and skeleton—that is, with an opening, d, through their panel portion. The plates need not be cast metal, nor exactly triangular in form; but the metal and form mentioned will be found preferable to any others. Wrought metal and various other suitable shapes, either skeleton or solid, might be used with great advantage as compared with trucks not supported by plates of any kind. The plates are firmly secured to the arch-bars $a-a$ by either bolts or nuts f f', or by rivets, or by other suitable strong fastenings, and when in position the arch-bars will be held by them from springing out of place, being firmly braced, stiffened, or stayed and supported against strains and pressure.

The truck-columns might have the supports for the arched bars formed on them; or flat bars of iron for supports might be bent into either triangular, V, or A form; or bars forming beveled knees or bearing-surfaces for the arched bars might be adopted as an equivalent. The latter construction—viz., supports forming beveled knees—would be the same as though the supports shown were cut in two at y y, Fig. 1, and the portion on the right side of y y were dispensed with.

The truck herein described is made of wrought-iron arch-bars, which are united at their ends upon the guides or supports for the journal-boxes. They are also kept apart by vertical columns and bolts, which latter pass through the bottom wrought-iron straps. This description of truck is almost universally adopted, with here and there slight modifications in its form and construction, and it is to this character of wrought-metal truck that my invention is to be applied, as hereinbefore described and shown.

I am aware that wrought-metal straps are well known as strengthening means applied to beams of steamboat-engines and many other structures; but I am not aware that web-plates, which form bearings on either side of the vertical columns of a truck-frame constructed of upper and lower wrought-metal arch-bars, have

ever been employed for the purpose and in the manner I have shown—*i. e.*, for preventing the arch-bars springing up between the vertical column-supports and the bearings for the 5 axle-journals—a difficulty which has been experienced with a great variety of the wrought-metal truck-frames by special tests.

I also am aware that a car-truck frame made entirely of cast-iron and in one piece is not 10 new; neither do I claim such a truck, for the purposes and results of my invention would not be accomplished were not my truck-frame made of wrought metal and such frame stayed and braced with bearing web-pieces made 15 separate from the arched bars and properly confined between the same.

I also am aware that wrought-metal frames of the general outline of the plan shown in my drawing, but not provided with the web- 20 plates, which form a bearing for the arched bars, is common, and I make no claim to the same separately considered; but

What I do claim as my invention, and desire 25 to secure by Letters Patent, is—

1. A wrought-metal side frame, A, for a car-truck, provided with confined wrought-metal arched bars, with sustaining-plates B applied and confined between them, forward of and also in the rear of the middle cross beam or 30 beams and between the converged portions *a a* of the frame A, substantially as and for the purpose described.

2. A wrought-metal truck-frame, A, consist-

ing of arched bars *a a* and plates B, said plates being firmly bolted or secured to and between 35 the bars *a a*, forward of and also in rear of the columns and bolts C, whereby bearings and abutments for the bars are afforded in front of and also rear of the middle cross beam or beams of a car-truck, substantially as described. 40

3. The combination, with the wrought-metal side frame, A, of angular plates B, applied between and secured in position against the bars *a a*, substantially as and for the purpose described. 45

4. The combination, with the wrought-metal arched bars of the truck-frame A, of skeleton angular plates B, said plates being applied between and secured in position against the bars, substantially as and for the purpose described. 50

5. The combination, with the wrought-metal arched bars *a a*, having sloping sides, of the metal plates B, said plates being applied between and secured in position against the converged ends of the arched bars, substantially 55 as and for the purpose described.

6. The wrought-metal truck-frame A, provided with a plate, B, on each side of its vertical columns and bolts C, and between its arched bars *a a*, substantially as and for the 60 purpose described.
